US0D1057472S

(12) United States Design Patent (10) Patent No.: US D1,057,472 S
(45) Date of Patent:  Jan. 14, 2025

(54) WALL MOUNT MOP CLIP

(71) Applicant: Haibo Yu, Guangdong (CN)

(72) Inventor: Liheng Ding, Xianning (CN)

(73) Assignee: Haibo Yu, Shenzhen (CN)

() Term: 15 Years

(21) Appl. No.: 29/956,305

(22) Filed: Aug. 6, 2024

(30) Foreign Application Priority Data

Jun. 26, 2024 (CN) 202430396095.8

(51) LOC (15) Cl. 08-08

(52) U.S. Cl.

(57) CLAIM

The ornamental design for a wall mount mop clip as shown and described.

DESCRIPTION

FIG. 1 is a perspective view of a wall mount mop clip showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the wall mount mop clip that form no part of the claimed design.

1 Claim, 8 Drawing Sheets
